UNITED STATES PATENT OFFICE

ERNEST WANAMAKER, OF CHICAGO, ILLINOIS, ASSIGNOR TO KULP THEFTPROOF LAMP COMPANY, OF CHICAGO, ILLINOIS, A CORPORATION OF ILLINOIS

LOCKING MEANS FOR ELECTRICAL APPARATUS

Application filed December 17, 1927. Serial No. 240,655.

This invention relates to locking means or devices for locking electrical apparatus within supporting sockets and has particular reference to devices of this character for rendering electric lamp bulbs, plug fuses, and the like, theftproof.

The subject matter of this invention comprises a theftproof electric lamp so made that it may be inserted in a socket of the usual construction and yet which cannot be stolen or removed from the socket until after the lamp bulb or electrical apparatus has become broken and displaced.

The objects of this invention include the provision of a very simple, durable and inexpensive construction for the purposes desired, such construction embodying substantially the minimum number of parts and being dependable and certain in its operation.

In the accompanying drawing, which illustrates one embodiment of my invention, Fig. 1 is an elevational view illustrating an assembled lamp embodying my invention;

Fig. 2 is a central sectional view through the base of a lamp embodying this invention and showing the parts in assembled relationship; and

Fig. 3 is a detailed sectional view of a portion of the lamp base member and shell contact.

In general, the invention as illustrated may comprise an electric lamp bulb, 10, of standard construction, a base member, 11, adapted to be securely cemented upon the stem or neck, 12, of the lamp bulb and a threaded shell contact, 13, for embracing the base member, 11.

It will be understood that I do not desire to restrict the application of my invention to its use with lamp bulbs, since various other types of electrical apparatus, such as plug fuses, thermo-ionic valves, and the like, may be substituted for the lamp bulb, 10, and rendered theftproof in accordance with this invention.

The base member, 11, may comprise a cylindrical shell contact, 14, upon which the threaded shell contact, 13, is loosely fitted.

The shell contact, 14, may be secured to the shell contact, 13, by the use of one or more

areas of adhesive material, as at 15, for the purpose of initially fixing the shell contact against rotation relative to the lamp base and lamp.

It will be observed that when the base member, 11, is rotated as by grasping the bulb, 10, for inserting the lamp into a receptacle, the shell contact, 13, will also be rotated because of the adhesive connections, 15. In this manner, the threaded shell contact may be screwed into the receptacle. The lamp or other electrical apparatus may be thus inserted and removed from the receptacle as often as desired, as long as no abnormal rotational forces are exerted thereon. However, when it is desired to render the device theftproof, the threaded shell contact may be screwed home in a receptacle and then if an abnormal and additional force is exerted to screw the device further inwardly, the adhesive area or areas as at 15 will be disrupted. Thereafter, the shell contact 13 will be free for rotational movement in respect to the base member 11 and, accordingly, when an attempt is made to remove the lamp from its receptacle by turning the bulb the base member, 11, will merely freely rotate within the threaded shell contact and without exerting rotational force upon such contact. Hence, the bulb or other apparatus, together with the base member, 11, will be merely rotated and cannot be removed.

After the lamp or other electrical apparatus has become worn out so that it is desirable to remove the same, the operator may place a canvas or other bag over the glass portion of the lamp and thereupon break the lamp. The canvas bag will retain the particles of broken glass. Access may then be had to a flanged edge, 16, on the threaded shell contact for removal thereof by the use of pliers or other suitable tools.

The threaded shell contact, 13, may be permanently retained against longitudinal movement in respect to the lamp by means of the flange, 16, at the lower edge of the contact and a flange, 17, at the upper edge or end thereof. The flange, 16, is adapted to be spun over and to abut a beaded portion, 18, formed upon the base member near its lower

edge. The flange, 17, is adapted to be spun over a flange portion, 19, at the upper edge of the base member, 11.

From an inspection of Fig. 2, it will be observed that the lower portions of the flange, 16, may be located at a point which will be well within the receptacle member in which the lamp may be inserted. In this way, the receptacle member serves to prevent access to the threaded shell contact member and accordingly this member cannot be turned either inwardly or out of the receptacle by tampering while the lamp or other electrical apparatus is in operative condition.

As shown in Fig. 2, the interior of the base member, 11, may be filled with a suitable cement to cement the base member to the neck of the bulb in the conventional manner. At the upper end of the base member, 11, a center contact, 20, may be positioned and held in place by the use of an insulating end piece, 21, which may be tightly fitted or molded into the upper end of the base member, 11. Lead wires, 22 and 23, from the lamp filament or other electrical devices may be electrically connected to the contacts, 13 and 20, respectively, in any suitable and well known manner.

It will be noted that the areas of adhesive material, 15, as illustrated may be relatively small so that the same may be readily disrupted by a proper force of relative rotation of the base member and the contact 13. The exact dimensions of the areas of adhesive of course will depend on the strength of the adhesive material used. In order that the adhesive after disruption will not accumulate in quantities at one point between the two contacts, and cause sticking or binding of one contact in respect to the other when it is desired that the lamp be freely rotatable, I find it to be preferable to use a non-granular adhesive such as an animal or vegetable glue of good quality, or a water glass cement or other cementitious and preferably non-granular cement which may be applied and dried to form a highly tenacious thin film between the adjacent metallic surfaces of the contacts. As indicated in the drawings, the areas of adhesive are preferably applied adjacent the outer edges of the contacts so that after disruption the film particles in the adhesive will drop out of the device and not tend to accumulate and cause binding or jamming of the then rotatable bulb. Hence after disruption of such adhesive, no further resistance will be offered to the free turning of the bulb parts in respect to the threaded shell contact. Relatively thin liquid adhesives, for example as those above mentioned, are preferably used in order that the same may be uniformly applied and dried in firm adhering relationship with the intended areas, thus providing connections

which may be uniformly disrupted by pre-determined forces.

While I have described my improvements in detail and in connection with a preferred form thereof, I do not desire to be limited to such details or forms, since many changes and modifications may be made and the invention embodied in various different forms without departing from the spirit and scope of the invention in its broader aspects. Therefore, I desire to cover all modifications and forms coming within the language or scope of the appended claim.

What I claim as new and desire to be secured by Letters Patent of the United States is:

In combination, an enclosure for electrical apparatus, a cylindrical shell mounted on said enclosure, means for preventing unauthorized removal of the enclosure from the shell, said shell being provided with means for engaging a supporting receptacle by turning movement of said shell, and a film-like layer of non-granular adhesive initially fixing said enclosure against rotation with respect to said shell to normally permit insertion and removal of the shell with respect to a receptacle by turning said enclosure, said adhesive being purposely designed to be disrupted by the exertion of a predetermined force in the direction of further inward turning of the enclosure after seating of the same in the receptacle.

In testimony whereof I have signed my name to this specification.

ERNEST WANAMAKER.
